UNITED STATES PATENT OFFICE

169,716

SHOE HEEL

William J. Walsh, Lemay, Mo.

Application November 20, 1952, Serial No. 22,374

Term of patent 14 years

(Cl. D7—5)

To all whom it may concern:

Be it known that I, William J. Walsh, a citizen of the United States, residing at Lemay, St. Louis County, State of Missouri, has invented a new, original, and ornamental Design for a Shoe Heel, of which the following is a specification, reference being had to the accompanying drawing, forming a part thereof, in which:

Fig. 1 is a side elevation of a shoe heel, showing my new design;

Fig. 2 is a top view thereof;

Fig. 3 is a rear elevation thereof;

Fig. 4 is a front elevation thereof.

I claim:

The design for a shoe heel, substantially as shown.

WILLIAM J. WALSH.
